UNITED STATES PATENT OFFICE.

CHARLES L. SULLIVAN AND CARL VICTOR WIENBERG, OF MOUNDSVILLE, WEST VIRGINIA.

DESIGN FOR AN ARTICLE OF MANUFACTURE.

52,758.

Specification for Design.

Patented Dec. 10, 1918.

Application filed February 14, 1918. Serial No. 217,243. Term of patent 7 years.

To all whom it may concern:

Be it known that we, CHARLES L. SULLIVAN, a citizen of the United States of America, and CARL VICTOR WIENBERG, a subject of the King of Sweden, both residents of Moundsville, in the county of Marshall and State of West Virginia, have invented a new, original, and ornamental Design for an Article of Manufacture, of which the following is a specification, reference being had to the accompanying drawings, in which—

Figure 1 is a side elevation of a drinking glass embodying the new design; and—

Fig. 2 is a similar view of the opposite side of the glass.

The design, which consists of the configuration shown, is applied to drinking glasses, dishes, vases, and similar glass articles.

We claim—

The ornamental design for an article of manufacture, substantially as shown.

CHARLES L. SULLIVAN.
CARL VICTOR WIENBERG.
